ATTORNEY.

UNITED STATES PATENT OFFICE.

LUTHER G. BILLINGS, OF CLIFTON, NEW YORK.

DESIGN FOR A HANDLE-BAR.

SPECIFICATION forming part of Design No. 26,339, dated November 24, 1896.

Application filed August 28, 1896. Serial No. 604,223. Term of patent 14 years.

To all whom it may concern:

Be it known that I, LUTHER G. BILLINGS, a citizen of the United States, residing at Clifton, in the county of Richmond and State of New York, have invented and produced a certain new and original Design for Handle-Bars for Bicycles and Similar Vehicles, of which the following is a specification, reference being had to the accompanying drawings, forming part thereof.

Figure 1 is a plan view, and Fig. 2 an end view, of a handle-bar, showing my design.

The leading features of my design are the straight middle portion of the handle-bar extending in opposite directions from the center, the forwardly-projecting portions inwardly inclined toward each other and joined to the middle portion by curves of short radius, the rearwardly and outwardly inclined portions parallel with the forward portions and joining the latter by semicircular curves of longer radius, and the grips or barrel-shaped swells, one each side of the center on the straight middle portion and one at the termination of each rearwardly-extending portion, all said grips being in the same line and lying in the same plane.

In the drawings, A is the central cylindrical portion, and A' A' swelled continuations of the same.

B B are the sharp curves, bending forward one from the outer end of each swell A', flow-

ing smoothly into the straight angular part B', each of the latter being joined by a curve C of somewhat greater radius to a straight portion C', extending rearwardly on a line about parallel with the portion B'.

C² C² are swells formed on the latter and corresponding to the swells A' A'. They terminate in smoothly-rounded hemispherical ends C³ C³, reaching rearward to about the axial line of the part A.

The several straight and curved portions lie in practically the same general plane, as will be seen in Fig. 2.

The combination of straight and curved cylindrical portions is particularly pleasing to the eye and is rendered still more attractive by the introduction of the graceful swells A' and C². The latter, by reason of the fact that they lie in the same plane and are in line with each other, allow the rider to shift his hands from one pair to the other without otherwise materially changing his position.

I claim—

The design for a handle-bar for a bicycle, substantially as herein shown and described.

In testimony that I claim the invention above set forth I affix my signature in presence of two witnesses.

LUTHER G. BILLINGS.

Witnesses:

J. P. FIRENG,
JOHN A. DELVES.
